UNITED STATES PATENT OFFICE.

TRACY V. BUCKWALTER, OF CANTON, OHIO, ASSIGNOR TO TIMKEN ROLLER BEARING COMPANY, OF CANTON, OHIO, A CORPORATION OF OHIO.

PROCESS AND APPARATUS FOR MAKING BEARING ROLLS.

1,419,611.

Specification of Letters Patent. Patented June 13, 1922.

Application filed October 3, 1919. Serial No. 328,260.

To all whom it may concern:

Be it known that I, TRACY V. BUCKWALTER, a citizen of the United States, residing at Canton, in the county of Stark and 5 State of Ohio, have invented an Improved Process and Apparatus for Making Bearing Rolls, of which the following is a specification.

My invention is designed to produce rolls 10 from stock in the form of rods by rough turning, finishing turning, burnishing and cutting off operations performed in sequence.

The primary object of my invention is to 15 produce superior rolls rapidly, economically and accurately.

The characteristic features of the invention are disclosed in the following descriptions and the accompanying drawings setting forth a form of mechanism used in the 20 practice of the same.

In the drawings, Fig. 1 is a broken front elevation of mechanism used in the practice of the invention; Fig. 2 is a broken side elevation of details illustrated in Fig. 1 for 25 rough turning the rolls; Fig. 3 illustrates a broken side elevation of mechanism for the finishing turning of the rolls; Fig. 4 is a broken side elevation of details of the mechanism used for burnishing the rolls following the finishing turning operation; and 30 Fig. 5 is a broken side elevation in illustration of details of the mechanism for cutting off the burnished rolls.

The mechanism shown in the drawings, 35 for the purpose of illustrating the invention, comprises a revoluble head 1, which carries the revoluble chucks 2, 2', 2'' and 2''' separated by quadrants and adapted for holding the metal rods 3, 3', 3'' and 3''', 40 these rods providing the stock from which the rolls are produced continuously by the sequential operation hereafter described.

A rough-cutting tool 4 is carried by the slide 5 which is movable on the guide 6 45 transversely to the axis of the chuck 2 and is adapted to act laterally against the projected end of a rod 5 revolved by the chuck 2 to turn the same to the rough roll form 3^a.

A finishing turning tool, comprising a 50 roller 7 carried by the bearing 8 (which is adjustable in the slide 9 transversely to the axis of the chuck 2' to support the roll 3^b revolved thereby) and a cutter 10 carried by a slide 11 (which is adjustable in the slide 55 9 transversely to the axis of the chuck),

conforms to the contour desired in the roll 3^b. The slide 9 is movable in the guide 12 transversely to the axis of the chuck 2' and the cutter 10 moved thereby to effect the finishing turning operation simultaneously 60 with the rough turning of the roll 3^a.

A burnishing tool is formed by the burnishing rollers 13 and 14 carried by the respective slides 15 and 16, which are adjustable in the slide 17, (laterally with relation to the axis of the chuck 2'' for revolving the roller 3^c) to effect the desired pressure of the burnishing rollers on the roll to be consolidated and finished thereby, the slide 17 being movable in the way 18 so that 70 the roll 3^c will pass between the rollers 13 and 14 as they are moved transversely to and in contact with the roll.

A cutting tool 19 is carried by a holder 20 set in the slide 21 which is movable in the way 22 transversely to the axis of the chuck 2''' to cut off the burnished and finished roll 3^d as it is turned by the chuck in contact with the tool.

In the operation of the device, the chucks 80 2, 2', 2'' and 2''' are revolved simultaneously in the stationary head 1 (by well known means not shown) to perform the operations of rough turning, finishing turning, burnishing and cutting off the respective rolls 3^a, 85 3^b, 3^c and 3^d. The respective operations on these rolls having been completed, the slides 5, 9, 17 and 21 are retracted, and the head 1 is turned through a quadrant to bring the roughly turned roll 3^a into position for the 90 finishing turning operation, the finally turned roll 3^b into position for the burnishing operation and the burnished roll 3^c into position for the cutting off operation, the rod from which the roll is cut being moved 95 forward for engagement in its next position with the rough turning tool.

Having described my invention, I claim:

1. The process of forming bearing rolls which comprises the sequential operations 100 of revolving the stock successively in contact with a turning tool, a burnishing tool and a cutting off tool.

2. The process of forming bearing rolls which comprises the sequential operations of 105 revolving the stock in contact with turning mechanism and between burnishing rollers which are moved transversely to the axis of the revolving stock.

3. The process of forming bearing rolls 110

- which comprises the operations of revolving said rolls between burnishing rollers having a motion of revolution in contact with and a motion of translation across said rolls.
5. 4. The combination with a revoluble head and revoluble work holders carried thereby, of a roughing cutter, a finishing cutter, a burnishing tool and a cutting off tool arranged to act simultaneously on work carried by said holders.
- 10 5. The combination of a revoluble work holder, burnishing rollers between which

said holder revolves said work, and means for moving said rollers in contact with and transversely to said work.

6. The combination with turning mechanism and burnishing mechanism; of means for revolving work first in contact with said turning mechanism and thereafter in contact with said burnishing mechanism.

Signed at Philadelphia, in the county of Philadelphia and State of Pennsylvania, this 2nd day of October, 1919.

TRACY V. BUCKWALTER.
